POWER LAWN MOWER

Charles W. Butler, New York, N. Y., assignor to Toro
Manufacturing Corporation of Minnesota, Minneapolis,
Minn., a corporation of Minnesota

Application September 8, 1953, Serial No. 26,743

Term of patent 14 years

(Cl. D40—1)

Fig. 1 is a rear perspective view of a power lawn mower, showing my new design;

Fig. 2 is a top plan view of the housing;

Fig. 3 is a side elevational view of the housing;

Fig. 4 is a front end elevational view of the housing;
and

Fig. 5 is a rear end elevational view of the housing.

The characteristic features of the design reside in the housing shown in full lines.

I claim:

The ornamental design for a power lawn mower, substantially as shown and described.
